UNITED STATES PATENT OFFICE.

HARRY YARRINGTON ARMSTRONG, OF SPRINGFIELD, MASSACHUSETTS, ASSIGNOR TO
PACKAGE MACHINERY COMPANY, OF SPRINGFIELD, MASSACHUSETTS, A CORPORA-
TION OF MASSACHUSETTS.

PASTING MECHANISM.

1,187,801.

Specification of Letters Patent. Patented June 20, 1916.

Original application filed February 14, 1913, Serial No. 748,305. Divided and this application filed September 12, 1914. Serial No. 861,370.

To all whom it may concern:

Be it known that I, HARRY Y. ARMSTRONG, a citizen of the United States, and a resident of Springfield, in the county of Hampden and State of Massachusetts, have invented certain new and useful Improvements in Pasting Mechanisms; and I do hereby declare that the following is a full, clear, and exact description thereof, reference being had to the accompanying drawings, and to the characters of reference marked thereon, which form a part of this specification.

This invention relates to improvements in wrapping machines, and refers more specifically to a pasting mechanism for applying paste to the edge of a wrapper before the wrapper is finally folded upon the article.

My improvements have been designed for use in the type of wrapping machine shown in my prior application for U. S. Letters Patent, Serial No. 748,305 filed on the 14th day of February, 1913, of which the present application is a division, and designed for wrapping sticks of gum, but said improvements are capable of general adaptation where pasting mechanisms are required.

Only such parts of the machine as are necessary to an understanding of the invention are herein described, reference being made to said prior application for a full disclosure of the wrapping mechanism proper.

The chief object of the invention is to provide a paste-applying mechanism for wrapping and similar machines which will operate at high speed to apply paste evenly to the area to be pasted, and without liability of moving the wrapper or sheet to receive the paste.

Other objects of the invention are to improve the means for transferring the paste from the paste pot to the paste applying devices, and to other improvements in the paste pot.

The invention consists in the matters hereinafter set forth and more particularly pointed out in the appended claims.

In the drawings:—Figure 1 is a partial side elevation of a machine embodying my invention. Fig. 2 is a partial longitudinal section thereof. Fig. 3 is a section on the line 3—3 of Fig. 1. Fig. 4 is a section on the line 4—4 of Fig. 1. Fig. 5 is a section on the line 5—5 of Fig. 1. Fig. 6 is a per-

spective view illustrating the secondary wrapper head and a portion of the pasting mechanism adjacent thereto. Fig. 7 is a section on the line 7—7 of Fig. 1.

As shown in the drawings, 10 designates a magazine in which are stacked the gums 6 to be wrapped. The gums are forced from the bottom of the magazine by a plunger 11 through a guide way 12 and through a wrapper slot or channel 15. The gum is delivered to said slot or channel together with a wrapper 65 c which is fed into the wrapper recess 13 across the mouth of said slot by means of a paper feed and cutting mechanism designated, as a whole, by 16. The paper is wrapped on three sides of the gum while passing through the slot 15 and is delivered by the final stroke of the plunger into the upper notch 17 of a rotative wrapper head 18. Upon retraction of the plunger 11 the said head 18 is rotated through 180 degrees of a circle, thereby carrying the partially wrapped gum to the plane of the secondary wrapper slot 19. The partially wrapped gum is forced from the lower pocket of the wrapper head 18 by a second plunger 21 into and through the secondary folding slot 70 80 or channel 19 where the terminal side flap of the wrapper is folded upon the package. When passing through said secondary slot or channel the end flaps of the wrapper are folded about the gum in the manner described in my aforesaid prior application. The plunger 21 at the limit of its forward stroke carries the fully wrapped package 85 into a slotted secondary wrapper head 22 across the path of an outer or label wrapper d, delivered in front of said wrapper head onto a support 23. By this movement the outer or label wrapper is partially folded on the previously wrapped gum, and during the retraction of the plunger 21 the wrapper head 22 is rotated throughout 180 degrees of a circle so as to carry the partially wrapped gum to the receiving mouth of the tertiary folding slot 24. The gums are advanced through said folding slot by a reciprocating finger 25 arranged beneath the slot and provided with an upwardly projecting tooth 26 adapted, in the forward movement of said finger, (which is effected through the medium of a cam 27) to engage the forward 90 edges of the gums and to force them through

95

100

105

the said tertiary slot by pressure of one gum against another. The fully wrapped gums are finally discharged upon a raising screw 28 at the lower end of upwardly and rearwardly curved discharge chute 29. The outer wrappers *d* are contained in a confined bundle in the magazine 30 arranged above the secondary wrapper head and the wrappers are stripped one at a time from 10 the forward end of the bundle by means of a stripper roller 31 which directs said wrappers into the wrapper recess of which the support 23 constitutes the bottom.

After the label or outer wrapper has been 15 partially applied to the gum, and the secondary wrapper head has been turned 180 degrees to direct a partially wrapped package into the tertiary folding slot, the trailing edge or margin of the wrapper is brought to 20 lie against a pasting face 34 on the upstanding bracket 35. At this point paste is applied to the forward surface of the wrapper margin, which constitutes, when the margin is folded against the package, its inner face, 25 so that when the trailing margin of the wrapper is folded up against the package as it passes into the tertiary slot 24, the paste applied thereto causes the margin to adhere to the opposite or first folding margin of 30 the wrapper.

The paste mechanism is made as follows: 37 designates a short shaft which extends from front to rear of the machine and is mounted at one end in the bracket 35 and at 35 its other end in a bracket or bearing 38 of the machine frame. Mounted on the front end of the said shaft 37 is a collar 40. Extending through said collar and through the shaft is a rod or spindle 41, the said rod extending beyond said collar to constitute a bearing for the axially apertured paste applying arm 42. The said rod or spindle 41 is headed at its upper end to engage the outer end of the paste applying arm to hold 45 it thereon, and is detachably fixed in the collar 40 so that it may be endwise removed therefrom to permit the removal of the paste applying arm. As herein shown, this attachment is effected by means of a screw 45 which is screw-threaded in the collar and engages at its inner end an annular socket in the rod 41. The said paste applying arm is provided at its outer end with a paste applying projection or member 46 which is adapted 55 to be swung past the pasting face 34 in contact with the margin of the wrapper lying against said face. The said paste applying arm 42 is provided at its inner end with a miter gear 50 which meshes with a fixed beveled gear 51 formed on the face of 60 the bracket 35.

With this construction, when the shaft 37 is rotated it serves, by reason of its connection with the paste applying arm, through

the rod 41, to revolve said paste applying arm in a vertical plane about the axis of the shaft 37; the engagement of said gear on the paste applying arm with the stationary gear 51 causing the arm to simultaneously rotate about its own longitudinal axis. The 70 result of this arrangement is to give the paste applying member 46 a planetary movement. The member 46 is brought into contact with a paste bearing surface in one part of its orbit or path of travel to receive paste 75 and in another part of its orbit is brought into contact with the wrapper so as to transfer the paste to the wrapper. From the construction described, it will be seen that the paste applying member has a rolling contact with the wrapper, as distinguished from a wiping contact. This construction possesses the important advantage of avoiding the tendency of the paste applying member to shift or displace the wrapper when transferring the paste thereto, such as would occur if the said member passed with a wiping contact across the face of the wrapper.

The path of the paste applying member across the wrapper is a curved or arcuate 90 path. In order to avoid applying paste to the pasting face 34, when no wrapper is present, I may provide said pasting face with a recess or depression 54 opposite to the path of the paste applying member 46 as it 95 travels across the pasting face.

The means for transferring the paste to the paste applying member comprises a rotative disk 56 located beneath the shaft 37 and having one face substantially in the plane of the pasting face. Said disk rotates in the body of fluid paste contained in a paste pot 57, and is mounted to rotate on a shaft 58 which has rotative bearing in the wall of the paste pot. The upper wall of the paste pot 100 is provided with an opening through which the disk extends, and is provided also at one side of said opening with a guard or hood 60 having a curved lip 61 which partially overlaps the periphery of the disk. Said top 110 wall is hinged at 63 to one side of the paste pot so that the same may be swung upwardly to charge the paste pot, and the swinging wall is locked in position by means of a swinging or hinged locking latch 65 115 hinged to the paste pot wall and adapted to be swung upwardly into the notched portion 66 of the said swinging top wall.

68 designates a scraper arranged to scrape the excess paste from the rising side of the 120 disk. Said scraper is carried by the upper end of an arm 70 which is hinged at 71 to the lower side of the paste pot. The said scraper is pressed toward the disk by means of a spring 72 that surrounds a rod 73 which extends through said arm 70 and into the adjacent wall of the paste pot, the spring being interposed between said arm and a

shoulder at the outer end of said rod. The movement of the scraper toward the disk is limited by a screw-threaded stop 75 which is screw-threaded through the arm 70 and 5 bears against the adjacent wall of the paste pot, and said screw-threaded stop is locked in place by a lock nut 76, Fig. 5, that is screw-threaded to the stop and bears against the outer face of said arm 70. The said 10 paste disk shaft is geared to the paste applying arm shaft by means of the pinion 78 on the latter shaft which meshes with the gear wheel 79 on the paste disk shaft. The said paste applying arm shaft is driven 15 from a shaft 81 mounted in the frame of the machine through the medium of a beveled pinion 82 on said latter shaft which meshes with one face of a double beveled pinion 83 carried by a short vertical shaft 84 that is 20 mounted in bearings carried by the machine frame. The other gear face of the double pinion meshes with a pinion 86 fixed to the paste applying arm shaft 37.

In order to prevent the paste applied to 25 the trailing margin of the wrapper from objectionably smearing the under side of the secondary wrapper head 22, when the packages are forced from the pockets thereof into the tertiary folding slot 24, the sides of 30 the said wrapper head at the end openings of the pockets are depressed so as to leave laterally separated ribs or projections 90, as best shown in Fig. 6. These ribs or projections are made with sharp or narrow 35 edges so that paste that may adhere thereto, as the pasted flap wipes over the same, will be so small as to be negligible.

I claim as my invention:—

1. A paste applying mechanism comprising 40 a paste applying member and supporting and operating mechanism therefor constructed and arranged to give said member a planetary movement in a path carrying it into contact with the surface to which it is 45 to apply paste, and means for supplying paste to said member.

2. A paste applying mechanism comprising 50 means for positioning an article to which paste is to be applied, a paste applying member mounted to revolve about an axis in a path carrying it past and into contact with said article, means for revolving said member, and means for rotating said member about another axis to cause it to roll on 55 the surface of said article to apply paste thereto.

3. A paste applying mechanism comprising 60 a paste applying member having a revolving movement to carry it past a surface to which it is to apply paste and having a rotative movement to cause it to roll on said surface, means to revolve and to rotate said member, and a rotative paste transfer

disk against the face of which said member rolls in a part of its orbital path. 65

4. A paste applying mechanism comprising 70 a revoluble arm which is rotatable on its axis and is provided with a paste-applying member, and means to revolve said arm and to rotate it.

5. A paste applying mechanism comprising 75 a part having a face arranged to support a label or the like, while paste is applied thereto, a paste applying member having a bodily revolving movement to carry it past said face and having a rotative movement to cause it to roll on the label, and means to revolve and to rotate said member, said supporting face being recessed opposite to the path of said member. 80

6. A paste-applying mechanism comprising 85 a revoluble arm which is rotatable on its axis, means to revolve said arm and means to rotate the arm comprising a gear on the arm concentric to its axis of rotation and a fixed gear with which the first gear meshes.

7. A paste-applying mechanism comprising 90 a rotatable shaft, means to rotate said shaft, a bearing rod extending transversely through said shaft, an elongated paste-applying arm mounted on said rod for rotation about the axis of said rod and provided at its outer end with a paste-applying member, means to rotate said arm about said axis during the rotation of said shaft and the 95 consequent revolution of the arm, and means for supplying paste to the said member.

8. A paste-applying mechanism comprising 100 a rotatable shaft, means to rotate said shaft, a bearing rod extending transversely through said shaft, an elongated paste-applying arm mounted on said rod for rotation about the axis of said rod and provided at its outer end with a paste-applying member, a gear fast with said arm, a stationary gear with which the first gear meshes, a paste-pot and a transfer disk rotatable therein and projecting therefrom in contact with which said paste-applying member is 110 arranged to roll.

9. A paste-applying mechanism comprising 115 a paste-applying member mounted for bodily movement about an axis and for additional movement about another axis, mechanism for moving said member about both of said axes, and means for supplying paste to said member.

In testimony that I claim the foregoing as my invention, I affix my signature in the 120 presence of two witnesses, this 20th day of August, A. D. 1914.

HARRY YARRINGTON ARMSTRONG.
